UNITED STATES PATENT OFFICE

1,990,285

TIE SPACER

Joseph Jacobé, Odhill, Manitoba, Canada

Application August 19, 1933, Serial No. 685,802

3 Claims. (Cl. 254—44)

My invention relates to rail clamps such as are used in tie shifting operations, and has for its primary object to provide a clamp of this character of simple durable construction and readily applicable to, or removable from, a rail, providing an abutment to serve as a fulcrum point for leverage means in tie shifting.

It has been proposed to provide a rail clamp for such purposes embodying mechanical accessories either for attachment, or assisting in the attachment, of the clamp to the rail, or as a reinforcement therefor.

The present invention contemplates provision of a rail engaging clamp effectively attachable to the rail without reinforcing or bracing accessories. This is obtained by provision of clamping jaws engageable with the head and base flange of the rail and an intermediate projecting portion conforming substantially to the contour of the rail providing a clamp securely engageable with the rail and yet readily attachable or removable therefrom.

Other features and advantages of the invention will become apparent from the accompanying description.

In the drawing:

Fig. 1 is a vertical section of a rail supported on a cross tie and shown with my improved clamp engaged thereon.

Fig. 2 is a plan view of the clamp in engagement with a rail and illustrated in operative relation to a displaced tie.

Having reference to the drawing 1 indicates a rail supported on cross ties 2 and 3, the tie 3 being illustrated displaced from its proper location as through rail creeping or other causes. A crowbar 4 is shown used as a lever for shifting the displaced tie to its proper setting in the roadbed, the rail clamp serving as an abutment to provide a fulcrum point for operation of the crowbar.

My improved clamp includes a body member 5 laterally projecting when engaged with the rail and having an upper integral jaw 6 shaped to overlie the head of the rail and providing a depending rail engaging portion 7. The body 5 is further provided with a shoulder 8 engageable against the edge portion of the base flange of the rail and projectable somewhat below the lower edge of said base flange providing a working face that ensures a firm engagement therewith without interference with removal of the clamp. Said shoulder 8 and depending portion 7 provide the gripping or binding points of the clamp with the rail.

The body member 5 is shaped to provide an intermediate projecting portion 9 shaped to substantially conform to the contour of the side of the rail with its forward face disposed in comparatively intimate relationship with the web of the rail and its upper and lower surfaces conforming to the inclination of the under side of the rail head and upper surface of the base flange respectively.

In use the clamp is engaged with the rail in proximity to the tie to be shifted with the jaw 6 engaging the head of the rail and the shoulder 8 resting against the base flange, and when so engaged securely binds against lateral pressure. A lever, such as the crowbar 4, is inserted between the clamp and tie providing the necessary leverage means for shifting the tie.

The structural simplicity of the device will be apparent, a very efficient clamp being provided eminently suited for use by nonskilled labour such as is more usually employed in work of this character.

The nature and scope of the invention having been indicated and its preferred embodiment described what is claimed as new is:

1. A rail clamp of the class described comprising a body member having an integral jaw adapted for engagement over the head of the rail and an angular shoulder engageable against the edge portion of the base flange of the rail, said shoulder forming a working face adapted to provide a binding engagement with the outer edge portion of said base flange as opposed to a canting movement of the clamp.

2. A rail clamp of the class described comprising a body member having an integral jaw adapted for engagement over the head of the rail, a shoulder engageable against the edge portion of the base flange of the rail, said shoulder forming a working face adapted to provide a binding engagement with the outer edge of said base flange as opposed to a canting movement of the clamp, and an intermediate portion projecting in comparatively intimate relationship with the web of the rail.

3. A rail clamp of the class described comprising a body member having an integral jaw adapted for engagement over the head of the rail, a shoulder engageable against the edge portion of the base flange of the rail, said shoulder when so engaged extending below the lower edge of said base flange, and an intermediate projecting portion shaped to substantially conform to the contour of the side of the rail.

JOSEPH JACOBÉ. 55
